ROBERT C. MITCHELL, OF MOUNT VERNON, NEW YORK.

SMOKER'S STAND.

Application filed January 6, 1927. Serial No. 159,334.

This invention relates to certain new and useful improvements in smokers' stands, the object being to provide an exceedingly simple and yet durable and effective construction whereby smokers' waste, such as burnt matches, ashes, cigarette and cigar stubs, and the like may be placed in a suitable receiving tray and from thence conducted down to a waste-receiving receptacle so positioned that the odor therefrom will not escape. Another object is to provide a construction in which the waste-receiving receptacle proper may be made of glass as the most sanitary material that may be employed for this purpose, the said glass container or receptacle being protected and so held by the protecting means that it may be readily emptied at any time without removal therefrom. This and other objects and advantages will be apparent to one skilled in the art from a reading of the following description and an examination of the accompanying drawing in which—

Fig. 1 is a side elevation partly broken away and partly in section showing the several elements employed and their relative arrangement, the upper and lower part being shown as separated slightly;

Fig. 2 is a side elevation partly broken away and partly in section showing a modification.

1 represents a hollow base, which may be open at the lower end, while the upper end is contracted to form a neck 2. 3 is a waste-receiving receptacle preferably made of glass or similar material because of its sanitary character and its durability in this use. The neck 2 is provided with a thread, which may be formed thereon if desired, as shown in Fig. 1, while the upper end of the jar or receptacle 3 is correspondingly threaded whereby the jar may be firmly secured to the base 1 within the same so as to be protected thereby. 4 represents a packing washer which may be provided if desired. 5 represents a waste conducting tube which depends from a tray 6, so that waste deposited in the tray 6 will pass by gravity freely down through the tube 5 into the waste-receiving receptacle 3. The lower end of the tube 5 is provided with means whereby this tube section may be readily attached to or detached from the base 1. In the form shown, 7 represents the skirt secured to the tube 5, the same being provided with a threaded portion 8, which may screw onto

the threaded neck 2 of the base 1. 9 represents a spacer brace which may be provided within the skirt 7 to more effectively support the lower end of the tube 5 within the skirt when the construction is such as indicated in Fig. 1. It is obvious that the particular means for securing the waste-receiving receptacle 3 within the supporting base may be modified in many ways without departing from the spirit or scope of this invention, and the same is true of the tube connection.

In Fig. 2 I have shown one modification in which instead of forming the threads or interlocking devices directly on the neck of the base 1, I provide an insert or adapter which is formed separately, the same being indicated at 10. The base 1 is secured to the adapter 10 in any suitable way as by brazing or soldering. The upper outer portion of the adapter is constructed so that the tube portion may be readily attached thereto or detached therefrom. In the particular form shown I have indicated that the upper outer portion of the adapter 10 is threaded. In this same figure, the lower inner part of the adapter 10 is shaped to detachably receive the jar 3, a thread being shown in this instance.

It is desirable to have the jar secured tightly to the base so that in use, when it is desired to empty the waste-receiving receptacle 3, the user will remove the upper tubular part rather than to remove the jar 3. If the user should remove the jar 3 and fail to replace it, a smoker might inadvertently throw a burning match or lighted cigarette stub into the ash tray only to have it fall to the floor to the possible injury of the latter. To avoid this possibility, the jar 3 is secured so tightly that the user may readily open and empty the device by simply removing the upper tubular part, which manifestly renders the device unserviceable for its intended purpose until the parts are again assembled. Should the jar 3 become injured or broken, it may, of course, be removed through the bottom of the base 1 and a new one substituted. In the case of an ordinary so called "Mason" jar of glass such replacement or repair may be made at the cost of a very few cents. The base 1, however, adequately protects the jar so that by only some unusual occurrence can be jar be broken. If desired, the lower part of the base may be equipped with means to steady the same on the floor to resist upsetting, and

to this end I may provide in the lower part of the base a heavy metal ring 11, which tends to very substantially lower the center of gravity of the entire device, which, it will be understood, is preferably of such height that it is within easy access of a smoker either standing or sitting. It will be understood that when the stand is assembled there will be no obnoxious odors escaping therefrom from the contents within the receptacle. Furthermore, the tray will be free from the accumulation of waste so that even should the stand be tipped over, no waste will be spilled upon the floor or carpets adjacent thereto, and to that end it is desirable that the means for connecting the waste-receiving receptacle 3 to the base 1 should form a substantially gas-tight joint. It is also preferable that the joint between the removable upper tubular portion of the base 1 should be sufficiently tight to prevent the escape of such odors, and also to prevent the admission of oxygen. Thus, any lighted matches, cigar or cigarette butts contained within the jar will be quickly extinguished by the absence of sufficient oxygen therein to maintain combustion.

What I claim is:

1. In a smoker's stand of the character described, a hollow base, the upper part of which is provided with a contracted neck, a waste-receiving receptacle open at its upper end, means for detachably securing the upper end of said waste-receiving receptacle to said base adjacent to said neck, a tray having a depending waste-conducting tubular portion with means for detachably securing the same to the upper part of said base in line with said neck and with said tubular portion.
2. In a smoker's stand of the character described, a base having a contracted neck portion adjacent its upper end, means for detachably securing a waste-receiving receptacle in said base and to form a substantially gas-tight joint between the base and such receptacle, and an upper attachable and de-

tachable waste conducting tubular member for said base, said tubular member supporting at its upper end a waste-receiving tray. 50

3. In a smoker's stand of the character described, a hollow base having a contracted neck adjacent its upper end, said neck having on its inner surface means for detachably securing a waste-receiving receptacle 65 therein, and a removable waste conducting tubular portion with means for detachably securing the same to the outer side of said neck.

4. In a smoker's stand of the character described, a hollow base having a contracted neck adjacent its upper end, said neck having on its inner surface means for detachably securing a waste-receiving receptacle 65 therein, and a removable waste conducting tubular portion with means for detachably securing the same to the outer side of said neck, the means for securing the jar within the neck of the tubular section upon the neck comprising threads on the respective parts. 70

5. In a smoker's stand of the character described, a hollow base having a contracted neck adjacent its upper end, a waste-receiving receptacle of a size to be contained wholly within the hollow base, means for 75 detachably securing said waste-receiving receptacle to the neck end of said base, and an attachable and detachable waste conducting tubular member with means carried thereby for connecting and disconnecting the same 80 to said neck end of said base.

6. In a smoker's stand of the character described, a hollow base, having a contracted neck opening at its upper end, a tray having a depending waste conducting tubular portion with means for detachably securing the latter to the said base around the said neck opening, a waste-receiving receptacle open at its upper end and adapted to be contained wholly within said base with means for detachably connecting the same to said base within said neck opening. 90
